United States Patent Office.

MORITZ CROHN, OF ST. LOUIS, MISSOURI, ASSIGNOR TO HIMSELF, H. W. VOLKERS, AND GUIDO D'OENCH, OF SAME PLACE.

Letters Patent No. 70,418, dated November 5, 1867.

VETERINARY NARCOTIC INJECTOR.

The Schedule referred to in these Letters Patent and making part of the same.

TO ALL WHOM IT MAY CONCERN:

Be it known that I, MORITZ CROHN, of the city and county of St. Louis, and State of Missouri, have invented a new and useful Narcotic Injector for Veterinary Purposes; and I do hereby declare that the following is a full and clear description thereof, reference being had to the accompanying drawings, and to the letters of reference marked thereon.

In this invention a common smoking pipe may be used, the said pipe being provided with a cover to the bowl, from the top of which there is a flexible tube, the outer end of which is terminated in a rigid nozzle suitable for injecting purposes. At the base of the bowl or stem of the pipe there is a small bellows, by means of which air is forced through the burning narcotic, in the pipe-bowl, to the injecting pipe.

The object of this invention is to produce a cheap and convenient instrument, whereby the smoke of some burning narcotic may be injected into the mouth or rectum of animals, for the cure of certain diseases in which such treatment has been or may be found beneficial.

To enable those skilled in the art to make and use my improved narcotic injector, I will proceed to describe its construction and operation.

The drawings represent the improved instrument in elevation.

A is the bowl of a common smoking pipe, which is provided with a cap, a, from the apex of which there is a flexible tube, B, the said tube being connected by means of the coupling b with a nozzle, B', of some hard material, such as is commonly used for syringes. In the drawings, the coupling b is shown in section, so as to disclose the arrangement for attaching the nozzle to the end or the side of the said coupling, as may be most convenient at the time of using. A cap, b', is used to cover up the orifice not used by the nozzle B'. At the base of the bowl there is a stem, C, of wood, or some other non-conducting material, and to the end of this stem is attached a bellows or India-rubber bulb, C'. A portion of the back end of this bulb is broken out in the drawings, so as to disclose the small flap-valve c, affixed to the inner end of the base-plug c', which is perforated to admit air to the bulb. By alternately pressing and relaxing the bulb C' air is drawn into it through the valve c, and expelled through the bowl A and nozzle B'.

Having described my invention, what I claim is—

The combination and arrangement of the bowl A, the tube B B', and the bellows C' c, substantially as and for the purpose set forth.

In testimony of which invention I hereunto set my hand in presence of—

MORITZ CROHN.
